UNITED STATES PATENT OFFICE.

LUCILE L. WITTE, OF KIEL, WISCONSIN.

PHOTOGRAPH-ALBUM.

1,385,196.

Specification of Letters Patent. Patented July 19, 1921.

Application filed June 16, 1919. Serial No. 304,475.

To all whom it may concern:

Be it known that I, LUCILE L. WITTE, a citizen of the United States, residing at Kiel, county of Manitowoc, and State of Wisconsin, have invented new and useful Improvements in Photograph-Albums, of which the following is a specification.

My invention relates to improvements in photograph albums.

10 Modern photographs are mounted upon cards which are provided with side flaps adapted to fold upon and protect the photograph.

15 The object of my invention is to provide an album having sheets or leaves provided with retainers adapted to receive and hold photograph mounting cards of differing sizes, and to allow the cover flaps to freely fold or unfold without disturbing the retainers, said retainers, however, being adapted to so engage the card or mounting as to leave the photograph fully exposed to view.

20 A further object of my invention is to provide means for retaining the cover flaps normally in folded position and readily releasing them when it is desired to inspect the photograph.

In the drawings:—

25 Figure 1 is a view of one page and a portion of the cover of my improved album showing a photograph engaged by the retainers, the cover flaps being in folded position and the flap retainers being also in retaining position.

30 Fig. 2 is an enlarged sectional view drawn on line 2—2 of Fig. 1.

Like parts are identified by the same reference characters in both views.

35 Each leaf of my improved album is preferably composed of three sheets of cardboard, 1, 2, and 3, respectively. The sheets 1 and 3 are longitudinally slitted from a point near the top of the leaf to a point near its bottom, and in a manner to provide 40 groups of retaining bands 5, which are parallel to the outer margin of the leaf. The groups of bands are separated from each other by intervening strips or wider bands 6, which are secured preferably throughout 45 their length to the intermediate sheet of cardboard 2 by means of any suitable adhesive material. The sheet of cardboard 1 is also preferably secured in a similar manner to the sheet 2 along all of its margins, but 50 the retainer bands 5 are unsecured except at their top and bottom ends where they are

55 integrally connected with the top and bottom margins of the sheet 1. Therefore, each of the bands 5 may be individually and separately lifted from the plane occupied by the sheet to permit an insertion of the photograph mounting card underneath the lifted band.

60 Another set of bands 7, preferably composed of tape or other suitable fabric, are secured to the sheet 1 near its inner margin in a position with these bands extending transversely of the bands 5 to points near the outer margin of the sheet, where these bands may be detachably secured by means of snap 65 fastenings 8 of ordinary construction, or by any other suitable fastening means adapted to allow the outer ends of these bands to be readily engaged or disengaged from the outer margin of the sheet 1.

70 The sheet 3 will be similarly slotted longitudinally to provide retainer bands 5, intermediate gummed strips or fixed bands 6, with the margins of the sheet gummed or otherwise secured to the intermediate sheet 80 2, and with retainer bands 7 crossing the bands 5, and having their outer ends detachably secured by snap fastenings.

75 All other pages of the album are similarly formed, each page being preferably composed of 3 cardboard sheets with the outer sheets slitted nearly from top to bottom to form groups of retainer bands as above described. It is possible to dispense with the intermediate cardboard sheet, but 85 it is preferably used in order that the adjustment of photographs on one side of a page may not interfere with the adjustment or arrangement of photographs on the other side, it being desirable that each page in the 90 album should receive photographs on both sides to economize space.

85 A convenient means for securing the inner ends of the tapes or cross bands 7 is to pass their inner ends underneath the inner margin of the sheet 1 (or 3) preparatory to 100 adhesively securing such margin and band 7 to the intermediate sheet 2, the adhesive material thus being utilized to secure the bands, and also to secure the margin of the sheet 1 to the intermediate or backing sheet 2.

95 The inner margin of each leaf is preferably provided with a binding strip 10, composed of fabric gummed or otherwise secured to the leaf and also engaged and bound in an ordinary binding 11, flexibly 110

connected with the covers 12, whereby the various leaves of the album are secured together in book form.

In use, when it is desired to mount a photograph in the album, one of the cross bands 7 will be released from the leaf at its outer end, after which one of the bands 5 will be raised by inserting a paper cutter or the blade of a knife or other tool into the slit 10 at one side of the margin of the selected band to lift the band sufficiently to allow one cover flap of the photograph card to pass across the space underneath the lifted band, and then this flap will be drawn through until the margin of the mounting card is adjusted underneath the selected retainer band 5. Thereupon a retainer band 5 underneath the opposing margin of the photograph card is selected and lifted to 15 allow the other cover flap to pass underneath it. By selecting the appropriate bands 5, and by properly manipulating the card, it is obvious that the card may be quickly adjusted in a position with the lifted or selected bands engaging its side margins, and with the cover flaps folded over these bands to a proper covering position. Finally, the cover retaining tape or band 7 may be carried across the cover flaps and secured by 20 its fastening to the outer marginal portion of the page or leaf of the album. By having the strips 6 of no greater width than the smallest photograph card to be mounted in the album, and by having the retaining bands 5 narrow and arranged in groups as 25 above described, it is obvious that photograph cards of varying sizes and differing lengths and widths may be readily mounted in the album, and by having a plurality of 30 flap retaining cross bands it will be possible to release any one of them for the inspection of a photograph without releasing any covering except those controlled by the released band.

I claim:

1. A photograph album having leaves provided with substantially parallel flat card retaining bands arranged in groups extending from the top to the bottom margins thereof, said bands being grouped whereby a photograph card may be engaged adja-

cent to its edges by one band from each of two groups.

2. A photograph album having leaves provided with substantially parallel flat card 55 retaining bands extending uninterruptedly from the top to the bottom margins thereof, and with each leaf composed of a plurality of sheets adhesively connected with each other along their margins. 60

3. A photograph album having leaves including card receiving sheets slitted from top to bottom margins to form a series of card engaging bands, said bands being disposed in groups of narrow bands separated 65 from adjacent groups by a wider band.

4. A photograph album having leaves including card receiving sheets slitted from top to bottom margins to form a series of card engaging bands, and means for reinforcing each sheet at its margins and between some of the bands. 70

5. A photograph album having leaves including card receiving sheets slitted from top to bottom margins to form a series of 75 card engaging bands, in combination with flap retaining cross bands secured to the inner side margins of the leaves and having quick detachable connection with the outer margins of the leaves. 80

6. A photograph album having leaves each composed of a series of sheets having their margins permanently secured together in reinforcing relation, and having their outer sheets longitudinally slitted from top to bottom margins to form juxtaposed groups of card retaining bands, with intermediate wider strips, which are secured to the other sheet between said groups, and said leaves being also provided with flexible binder margins composed of fabric, and transverse bands also composed of fabric secured at their inner ends to the leaves and in quick detachable connection at their outer ends with the outer margins of the leaves. 95

In testimony whereof I affix my signature in the presence of two witnesses.

LUCILE L. WITTE.
